UNITED STATES PATENT OFFICE.

GEORGE AMBORN, OF CHAPINVILLE, CONNECTICUT, ASSIGNOR TO J. H. WILLIAMS & CO., OF BROOKLYN, NEW YORK, A CORPORATION OF NEW YORK.

TOOL-HOLDER.

1,120,783.

Specification of Letters Patent. Patented Dec. 15, 1914.

Application filed February 12, 1912. Serial No. 677,157.

To all whom it may concern:

Be it known that I, GEORGE AMBORN, a citizen of the United States, residing at Chapinville, in the county of Litchfield and State of Connecticut, have invented certain new and useful Improvements in Tool-Holders, of which the following is a specification.

This invention aims to provide certain improvements in tool holding devices for lathes or the like, whereby the fastening device has and even bearing on the tool, and whereby other advantages may be secured, as stated in detail in the following specification.

The accompanying drawings illustrate embodiments of the invention.

Figure 1 is a longitudinal section; Figs. 2 and 3, sections on the lines 2—2 and 3—3 of Fig. 1 respectively; and Fig. 4 an end view of one embodiment of the invention; Fig. 5 is a longitudinal section of another embodiment; Figs. 6 and 7 are respectively a longitudinal section and plan of still another embodiment; Figs. 8 and 9 are respectively a longitudinal section and plan of still another embodiment.

Referring now to the embodiments of the invention illustrated, the complete tool holding device comprises a shank A and a holder proper B, the tool C being clamped between the shank and the holder, with or without the intermediation of other parts, as hereinafter described. The holder proper B embraces the top and bottom of the tool C, and extends backward to form a stud D (Fig. 1) which fits loosely as shown into an opening E passing from front to rear through the shank, and extends through 40 at the back of the shank where it is provided with a screwthreaded end F upon which is a nut G bearing against a washer H which has a convex face bearing against a concave face on the rear of the shank. Or 45 the clamping may be effected by using a stud D' (Fig. 6) which is hollow and internally screwthreaded, and which is engaged by a screw F' having thereon a head G' bearing against a washer H' which in turn bears 50 against the rear face of the shank.

There is sometimes a variation or lack of parallelism between the outer and inner faces of the cutter. In order that this lack of parallelism shall not introduce bending 55 strains in the clamping devices, I provide

that the opposite clamping faces shall be adapted to have a relative rocking movement toward and from each other. This rocking movement may be secured in either one or in both of the opposite clamping 60 faces.

The device of Fig. 1 shows a separate rocker J having a convex rear face bearing against a concave forward face of a ring or collar K which bears against the forward 65 face of the shank. Now when the nut G is turned and a clamping strain is put on it, the tool bears inwardly against the rocker J, and the latter will rock sufficiently to make a perfect contact or bearing against the tool, 70 and at the same time its convex rear face will form a good bearing against the collar K, and through this collar against the shank. The rocker J is provided with a pin L entering loosely a socket in the end of the 75 stud D, which will prevent the detachment of the rocker. This will save the rocker's being lost in the manipulation of the holder to introduce and withdraw a tool. The clamping face of the rocker, that is to say, 80 the face which engages the tool, is serrated as shown at J' so as to bite into it, and not only to hold the tool against longitudinal slipping, but to cause the rocker to adjust its angular position perfectly in accordance 85 with any variation in the clamping face of the tool.

For securing an angular adjustment of the tool in a plane perpendicular to the clamping screw F the collar K is at its rear 90 face provided with radial grooves and projections M which interlock with similar grooves and projections on the forward face of the shank A. The projections on these parts are triangular in cross-section, so that 95 the collar will automatically find its way into interlocking position, thus insuring proper engagement when a tool is clamped in place.

By setting the collar K and with it the 100 rocker J and holder proper B in the desired angular position, the tool is correspondingly set. Such a provision for angular adjustment is not an essential feature of the device, though preferable.

Fig. 5 shows a construction the same as Figs. 1 to 4, with the addition of an outer rocker J² between the holder proper and the outer face of the cutter C. The rocker J² is loosely mounted in the holder B by 110

means of pins N on the sides of the rocker entering loosely into openings O in the side arms of the holder so as to prevent loss of the rocker, and at the same time to 5 permit it to freely adjust itself to the clamping face of the tool. This construction allows for a slight angular adjustment of the outer end of the tool toward and away from the shank. For this purpose the tool 10 may be held in any angular position desired, the rockers J and J² adjusting themselves accordingly and the holder being then clamped.

Figs. 6 and 7 show a construction similar 15 to that of Figs. 1 to 4. The rocker J³, however, rests directly against the shank A, the latter being provided with a series of radial slots P. For effecting an angular adjustment of the tool the rocker J³, and 20 with it the holder B, are turned so as to drop the rocker into the desired slots P. This makes a positive lock like that made by the projections M of Figs. 1 to 4, though it does not allow of as nice adjustment; and 25 the angular projections M automatically insure a proper locking engagement of the parts, while the square-edged grooves P do not automatically fall into engagement with the rocker. The rocker might possibly be 30 fastened in a position where it does not engage one of the grooves P, and might thus give trouble when strain is put on the cutter. The rocker J³ is held in place by means of the pins Q projecting from its 35 sides and embracing one of the side arms of the holder B.

In Figs. 8 and 9 a collar K' has a slot 40 across its outer face for direct engagement of the tool C, and has fine triangular radial teeth M for engagement with similar radial teeth on the shank, whereby a nice angular adjustment can be effected and the engagement is made automatic as above explained. 45 A rocking movement of the holder proper B is permitted by making the stud F² loose in the shank, and by the use of the convex washer H² so as to permit the relative rocking movement of the clamping faces desired to cause them to take an even bearing 50 upon the opposite faces of the tool. The washer H² is made integral with the nut G² in the construction illustrated; but it may be separate, as in the previous figures. With respect to the rocking capability of 55 the holder proper this construction is similar to that of Figs. 1 to 5. But in this construction the bearing of the lower edge of the tool is fixed and there is no rocker such as J or J², and as the tool is clamped the 60 holder proper B will necessarily rock so as to come to a flat bearing on the upper edge of the tool; whereas in the devices of Figs. 1 to 5 the rocker or rockers J and J² will

ordinarily adjust themselves to the edges of the tool, and the loose fit of the stud D 65 in the opening E through the shank together with the convex bearing face of the washer H will serve chiefly to ease any transverse strain upon the stud by permitting a slight rocking movement of the holder 70 proper relatively to the shank whenever necessitated by the occurrence of such a strain.

What I claim is:—

1. A tool-holding device including in 75 combination a shank and a holder proper between which a tool is to be clamped, said holder having a slot through which the tool is passed and having a threaded stud extending through the shank, and a nut engaging 80 said stud and bearing against said shank by which the holder is drawn toward the shank to clamp the tool in place, said holding device being adapted to permit a slight rocking of the opposite clamping faces relatively to each other so as to adjust themselves automatically to an even bearing against the opposite sides of the tool as said stud is drawn up by said nut.

2. A tool holding device comprising in 90 combination a shank and a holder proper between which a tool is to be clamped, said holder being adapted to rock so as to adjust itself to the face of the tool.

3. A tool-holding device including in 95 combination a shank and a holder proper between which a tool is to be clamped, said holder having a slot through which the tool is passed and having a threaded stud extending through the shank, and a nut engaging 100 said stud and bearing against said shank, by which the holder is drawn toward the shank to clamp the tool in place, said holder being adapted to rock so as to adjust itself to the face of the tool. 105

4. A tool-holding device including in combination a shank A having a transverse opening through its end and a holder proper B, between which shank and holder a tool is to be clamped, said holder having 110 a stud F² passing loosely through said opening and having a slot substantially parallel with the shank and through which the tool passes, said stud being threaded at its end, and a nut on said end having a rocking bearing against the shank by which the holder is drawn toward the shank to clamp the tool in place and is adapted to rock 115 so as to adjust itself to the face of the tool.

In witness whereof, I have hereunto 120 signed my name in the presence of two subscribing witnesses.

GEORGE AMBORN.
